Primary Examiner — Susan Bennett Hattan*Assistant Examiner* — Leanne Was(74) *Attorney, Agent, or Firm* — Hamilton, Brook, Smith & Reynolds, P.C.(57) **CLAIM**

The ornamental design for a beverage container assembly, as shown and described.

DESCRIPTION

FIG. 1 is an exploded perspective view of an embodiment of our design of a beverage container assembly including a solid wrapper, the center strainer and screw threads being shown in broken lines.

The beverage container assembly has generally cylindrical symmetry. The broken lines depict portions of the beverage container assembly that form no part of the claimed design.
